SELECTIVE SEAM DETECTOR

Charles G. Richardson, Springfield, Vt., assignor to Parks & Woolson Machine Company, Springfield, Vt., a Corporation of Vermont

Application March 3, 1932. Serial No. 596,449

12 Claims. (Cl. 26—17)

This invention relates to selective feelers adapted for use in cloth finishing machines such as, for example, a cloth shearing machine, to protect the seamed ends of two pieces of cloth against injury when passing through the shearing or other cloth finishing elements of the machine.

In such cloth finishing machines it is customary, in order to expedite the feeding of pieces of cloth through the machine, to sew a considerable number of lengths of cloth end to end so as to run them through the machine in a continuous strip. Obviously, this transverse seam or sewing produces an extra thickness of the cloth, which will interfere with the proper operation of the cloth finishing elements, particularly the shearing elements, when the strip is fed continuously through the machine.

While the concept of using a seam detecting feeler for controlling means for opening the shearing elements, or otherwise protecting the seam against injury, as the cloth approaches the operating or shearing line, is old yet the automatic seam detecting feelers of the prior art have been subject to severe criticism and objection because the feeler mechanism is equally actuated by a seam or by bunches, knots or slubs on the face of the cloth of relatively narrow extent or width. The feeler mechanism constituting the present invention is constructed and arranged to act on a selective principle which avoids operation of the seam-protecting mechanism or shear opening mechanism through contact with a passing slab, bunch or other protuberance of relatively narrow width transversely of the cloth, while at the same time insuring action or energizing of the seam-protecting means by each transverse seam or sewing that passes by the feeler.

The underlying principle of the present invention is embodied in a feeler mechanism that will begin its movement whether engaged by a transverse seam, or by a narrow bunch, or other protuberance, but which fails to complete the necessary movement to energize the seam-protecting means by automatically disengaging itself after the initial movement from a narrow bunch or protuberance.

This and other features of the invention will be particularly described in the following specification and will be defined in the claims hereto annexed.

In the accompanying drawing I have illustrated a simple and convenient embodiment of the principles of this invention and also a modified form thereof.

55 In the drawing

Fig. 1 is a front elevation illustrating in a diagrammatic manner the arrangement of parts of the apparatus as they are arranged at the front of a cloth shearing machine, or other cloth finishing machine to be actuated by protuberances on the face of the cloth.

Fig. 2 is a plan view of the apparatus illustrated in Fig. 1 showing the parts in relation to the upward travelling piece of cloth.

Fig. 3 is a left hand elevation of the feeler mechanism in association with suitable cloth guiding members that guide the cloth across its front.

Fig. 4 is a front elevation illustrating a modified construction of feeler apparatus.

While I have shown in other pending applications selective feeler mechanisms employing a plurality of feeler fingers cooperatively arranged to require movement of a predetermined number of feeler fingers in order to effect the energizing of seam-protecting means, the present improvement differs from such selective feeler mechanism in that the feeler mechanism herein is made selective not through the use of a plurality of coacting feeler fingers but through the agency of a single feeler finger which is made selective by making provision for the disengagement of the feeler finger from narrow protuberances on the cloth before the feeler mechanism effects the energizing of the seam-protecting means, while such disengagement does not occur when the feeler finger is engaged by a transverse seam passing by it.

In the preferred form of the invention illustrated in the drawing, the feeler finger 1 is pivotally mounted on a rock shaft 2 that is disposed behind the face of the upward travelling cloth and in a plane at substantially right angles to the face of the cloth. The body of the feeler finger 1, therefore, lies in substantial parallelism with the plane of the adjacent face of the cloth and slightly separated therefrom, provision being made for engaging a passing protuberance on the cloth by providing the feeler with a forwardly projecting cloth-engaging member or part 1^a extending for a short distance transversely of the cloth. This feeler finger 1 is slidably mounted in a yoke or fork 3 that is fastened to the shaft 2 and between the arms of the fork is arranged a compression spring 4, one end of which thrusts against an arm 3^a of the fork while the other end thrusts against a stop or pin 5 carried by that portion of the feeler finger that lies between the two bearing or supporting arms comprising the fork. The feeler finger is made oblong in cross section to conform to oblong bearings in

the fork to prevent turning or twisting of the feeler finger when engaged by the cloth.

The rock shaft 2 carrying the fork, which affords a support for the slideable feeler finger, is provided with a downwardly projecting arm 6 which is connected through a pivotal link 7 with a rocker arm 8 swingable about a fixed axis and carrying at its lower end an antifriction roller engaging the free end portion of a stop finger 9 which is secured to another rock shaft 10. On this rock shaft 10 is secured the pawl 11 that is rocked into interlocking engagement with a ratchet 13 by means of a spring 12, which spring is normally prevented from acting by the engagement of the stop finger 9 with the roller on the rocker arm 8.

Since the cloth-engaging member 1^a of the feeler finger covers only a relatively narrow space across the face of the cloth, the great majority of the slubs or protuberances, that are scattered here and there through the face of the cloth, will not engage the feeler at all but when such a protuberance approaches in line with the portion 1^a of the feeler, the feeler is engaged and rocked. Such rocking movement of the finger in a plane parallel with the face of the cloth causes a clockwise rocking movement of the rock shaft 2. The link 7 transmits the rocking movement to the rock arm 8, but if the rocking movement of the feeler finger and rock shaft is slight the roller will not clear the stop finger 9, as the parts are proportioned, but a further continuation of the rocking movement will shift the roller clear of the stop finger 9 allowing the spring 12 to actuate the pawl into engagement with the ratchet, which ratchet when so held against rotation acts to start other mechanism described in the earlier joint application of myself and John W. Hogue, Serial No. 591,829 but which forms no part of the invention claimed in this application and is therefore not shown or described in detail. It is sufficient to state that through the release of the rock shaft 10 seam-protecting mechanism of any suitable type is energized or rendered active.

There is, of course, no need of actuating the feeler mechanism to energizing position when it is engaged only by a knot, slab or bunch and therefore provision is made for disengaging the feeler finger by imparting a movement thereto transversely of the cloth, so that its cloth-engaging tip 1^a will be moved out of engagement with the actuating protuberance on the cloth.

To effect this disengagement the feeler finger is slidably mounted in the yoke 3, as previously explained, and is provided with a projecting boss or lug 1^b extending rearwardly into the path of the revolving teeth on the continuously rotated wheel 15.

As shown in Fig. 1, the feeler normally lies slightly below the level of the wheel 15 so that the lug 1^b is not engaged by the revolving teeth of the wheel. When, however, the feeler finger is lifted a short distance by the travel of the engaging protuberance on the cloth, the lug 1^b is carried into the plane of the revolving wheel 15 and is slid in the direction of its longitudinal axis through its bearings in the fork 3. This sliding movement transversely of the cloth serves to disengage the feeler finger from its actuating slab or bunch so that the feeler, relieved of the actuating engagement with the bunch, is free to return to normal position of rest. As before explained, this slight movement is not sufficient to disengage the roller arm 8 from the stop finger 9. However, should a transverse seam of the

cloth engage the feeler finger tip, such transverse movement or displacement of the feeler finger will not disengage it from the seam which extends entirely across the cloth. Consequently, the upward swing of the feeler finger will continue a sufficient distance to swing the roller carrying arm free from the stop finger 9, thereby energizing the seam-protecting mechanism. One advantage of using a power driven member, such as the tooth retracting wheel 15, is that the sliding of the finger against the yielding resistance of the spring is effected with the minimum of drag on the cloth, although the spring used in any case should be a rather light one.

In Fig. 4 is shown a modified form of the invention in which the shifting of the finger to disengage it from a slab or the like is effected by means of a guide 18 adjustably secured to a supporting rod 19 by set screw engagement. This guide, by its engagement with a roller 20 carried by the finger, imparts a lateral shifting or retracting movement to the finger which serves to disengage it from a knot or slab in the first part of its upward movement, while allowing continuance of the upward movement a sufficient distance to energize the seam-protecting means whenever the feeler is engaged by a seam across the cloth. The slideable finger 1 telescopes through the arms of the yoke 3, as before, and rocks the arm 6, but as shown in Fig. 4 instead of extending the stop finger 9 a substantial distance beyond the end of the rocker arm 8, lost motion, before releasing the finger, is secured by providing the connecting link 7 with a pin and slot connection with the rocking arm 6, so that the first part of the rocking movement of the rock shaft 2 and arm 6 does not shift the roller arm 8 but a continuance of the rocking movement, after the pin has engaged the end of the slot, acts to clear the roller from the finger 9. In this form of the invention there is no spring tension to be overcome but merely the weight of the feeler parts which act to return the feeler in both forms to normal position of rest.

As the cloth travels upward in front of the feeler it is guided by any suitable guide means, such as cross bar 16 and the guide rods or rollers 17 located at the front of the machine. The lower roller or guide 16 is positioned at a high enough level, relative to the normal position of the feeler tip, to maintain engagement of the seam with the feeler tip up to a height where the feeler has functioned to energize the seam-protecting means and then guiding the cloth-seam away from engagement with the feeler after the feeler has functioned. This arrangement of the guide effects the easy disengagement of the seam from the feeler without exerting any additional stress on the cloth when freeing the seam from such engagement.

What I claim is:

1. A selective feeler mechanism for energizing seam-protecting means embracing a feeler finger arranged to be engaged and moved to energizing position by a passing cloth-seam extending transversely of the cloth, and means for shifting said finger transversely of the cloth to release the finger from engagement with a narrow protuberance on the cloth before the feeler is moved to energizing position.
2. A selective feeler mechanism for energizing seam-protecting means embracing a feeler finger pivotally mounted on an axis substantially perpendicular to the plane of the cloth travelling by it and positioned to be engaged by a protuberance

- or seam extending across the width of the cloth and moved thereby about its axis to energizing position, and means for disengaging said feeler from a narrow protuberance on the cloth before the feeler reaches energizing position. 5
3. A selective feeler mechanism for energizing seam-protecting means embracing a feeler arranged in position to be engaged and moved by a protuberance on the cloth, said feeler having both a swinging and a sliding movement, the latter movement acting to disengage it from the narrow protuberance before reaching energizing position. 10
4. A selective feeler mechanism for energizing seam-protecting means embracing a feeler arranged in position to be engaged and pivotally moved by a protuberance on the cloth, and means for interrupting the pivotal movement of the feeler before reaching energizing position when the feeler is engaged by a narrow protuberance on the cloth. 15
5. A selective feeler mechanism for energizing seam-protecting means embracing a rockable and slidable feeler finger normally positioned to be engaged and moved by a passing protuberance on the cloth, means for effecting said sliding movement before the feeler has reached energizing position and thereby disengaging it from a narrow protuberance on the cloth in order to prevent the feeler from energizing seam-protecting means. 20
6. A selective feeler mechanism embracing a feeler finger arranged in close proximity to the face of the cloth and movable in a plane parallel to the face of the passing cloth and positioned to be engaged and moved by a protuberance on the cloth, means for retracting the feeler transversely of the cloth and thereby disengaging it from a narrow protuberance on the cloth while permitting the continuance of the engagement between the feeler finger and a transverse seam until the feeler has reached energizing position. 25
7. A feeler mechanism for energizing seam-protecting means embracing in combination with suitable cloth guiding means, a feeler finger positioned in close proximity to the face of the cloth that is opposite the guiding means and movable when engaged by a transverse seam of the cloth to energizing position, the guiding means being arranged in relation to such energizing position to direct the seamed portion of the cloth away from said feeler finger to release it from engagement therewith beyond the energizing position of the feeler, said feeler being also movable in a direction transversely of the cloth to release it from engagement with a narrow protuberance on the cloth before the feeler finger reaches energizing position. 30
8. A feeler mechanism for energizing seam-protecting means embracing a feeler finger disposed to be engaged and moved to energizing position by a transverse seam across the cloth, means for guiding the seamed portion of the cloth out of engagement with the seam beyond the energizing position of the finger, and means for shifting the finger transversely of the cloth before the finger has moved to energizing position. 35
9. A feeler mechanism for energizing seam-protecting means embracing a rock shaft perpendicular to the face of the travelling cloth, a seam engaging feeler finger carried by said rock shaft to rock the same when engaged and moved by a seam, means for moving said finger transversely of the rock shaft before the finger is moved to energizing position, and means actuated by the rock shaft after such transverse movement of the finger to start the seam-protecting means in action. 40
10. A feeler mechanism for energizing seam-protecting means embracing a rock shaft perpendicular to the face of the travelling cloth, a seam engaging feeler finger slidably carried by said rock shaft and movable transversely of the rock shaft against yielding resistance, a rotating member arranged to engage said feeler finger after its initial seam-induced movement to impart transverse movement to the finger against such yielding resistance before the feeler finger is moved by the seam to energizing position, whereby the feeler finger is disengaged from a narrow protuberance on the cloth but continues in engagement with a transverse seam on the cloth. 45
11. A feeler mechanism for energizing seam-protecting means embracing a feeler finger movable about a pivotal axis when engaged by a seam on the cloth travelling by and also movable transversely of its axis, guiding means arranged to engage and retract said feeler finger as it is moved about its axis by the travel of the cloth, and means actuated during the latter part of the seam-induced movement of the feeler finger to cause energizing of the seam-protecting means. 50
12. In a feeler mechanism for controlling seam-protecting means of a cloth finishing machine, a feeler finger mounted in position to be engaged by a passing protuberance on the cloth and movable by such engagement a predetermined distance with the cloth, and means for disengaging said feeler finger from a narrow protuberance before reaching its operative position for acting on the seam protecting means while allowing further movement of the feeler finger to active position when the feeler finger is engaged with a relatively long protuberance such as a seam across the cloth. 55
